UNITED STATES PATENT OFFICE.

JOHN BELL CARTER, OF CARTERVILLE, ILLINOIS, ASSIGNOR OF ONE-HALF TO AMIEL BORGHI, OF HERRIN, ILLINOIS.

MAIL DELIVERY AND RECEIVING APPARATUS.

1,105,181.

Specification of Letters Patent.

Patented July 28, 1914.

Application filed July 19, 1913, Serial No. 780,047. Renewed April 1, 1914. Serial No. 828,907.

To all whom it may concern:

Be it known that I, JOHN BELL CARTER, a citizen of the United States, residing at Carterville, in the county of Williamson 5 and State of Illinois, have invented a new and useful Mail Delivery and Receiving Apparatus; and I do hereby declare the following to be a full, clear, and exact description of the invention, such as will enable others skilled in the art to which it 10 appertains to make and use the same.

This invention relates to the art of handling mail bags and more particularly to a new and useful improved mechanism for 15 the exchange of mail bags between a moving train and a holder arranged adjacent the track.

One of the objects of the invention is to provide a simple, practical and reliable apparatus for handling mail bags in the above 20 manner without injuring their contents.

As another object of the invention it is the aim to provide the mechanism on the holder and the apparatus on the moving 25 train with similarly constructed devices, automatically actuated by the exchanged bags for clamping each respective bag as exchanged.

Another object of the invention is the arrangement of a member of the mechanism 30 of the train in such wise, that not only the device for clamping the bag to be received, is released, when the said member is actuated by the received bag, but which member acts 35 to assist in releasing the bag to be delivered to the mechanism of the holder.

The annexed drawings are for illustrative purposes only, therefore, in reducing the invention to practice, the inventor reserves 40 the right to detailed alterations, provided they fall within the scope of what is claimed.

The invention comprises further features and combination of parts, as hereinafter set forth, shown in the drawings and claimed.

45 In the drawings:—Figure 1 is a plan view partly in section and partly in elevation, showing the mail bag exchange mechanism in the act of exchanging mail bags, and as applied to a moving car and a holder. Fig. 50 2 is a sectional view on line 2—2 of Fig. 1, showing the exchange mechanism in elevation. Fig. 3 is an enlarged side elevation of a mail car showing its mail delivery and

receiving mechanism as applied in the doorway showing parts in section. Fig. 4 is a 55 sectional view on line 4—4 of Fig. 1. Fig. 5 is a detail view showing how a bag is clamped when received by the mechanism of the car, and how another bag is being released.

60 Referring more particularly to the drawings, 1 designates a post or holder, to which a plate or the like 2 is fastened by the screws, bolts or similar devices 3. Carried by the plate is a member 4 having an arm 5 and an 65 angular arm 6, the end 7 of which is provided with a clip 8 to receive the loop of a mail bag 9. The arm 5 terminates in clamping members 10, secured by a bolt and nut 11 about a tubular member 12.

70 Extending transversely of the doorway or opening 13 of the car 14 is a cylindrical bar 15, one end of which is secured in a socket 16 of the plate 17 which is secured to the car. The other end of the bar terminates in a 75 downwardly extending arm 18 fitting the U-shaped or arch-shaped straps 19, which are secured to the car.

A second tubular member 20 is swiveled upon the rod 15, and adapted to be swung 80 to either a vertical or horizontal position. A brace bar 21 is likewise at 22 on the bar 15 and is fixedly connected at 23 to the tubular member 20.

85 Each tubular member is provided with a mail bag receiving mechanism similarly constructed. The mail receiving mechanism of each tubular member comprises a semi-circular arm 24 having a ring 25 at one end and a semi-cylindrical clamping plate at the 90 other end. This semi-cylindrical clamping plate 26 fits the outer portion of the tubular member, there being a correspondingly-shaped plate 27 opposite the plate 26. By means of the plates 26 and 27 and the bolts 95 and nuts 28, the arm 24 is held to the tubular member. Each tubular member is constructed with slots 28'. Arranged in each tubular member is a plunger 29 having a pin 30 extending transversely thereof, which 100 pin extends through the slots 28. Interposed between the plunger and an interior annular shoulder of the tubular member is a spring 31, the tendency of which is to normally hold the plunger in one end of the 105 tubular member and the plunger rod 32 ex-

tended, in order to clamp a mail bag against the ring 25. The annular shoulder on the interior of the tubular member is designated by the numeral 33. Pivoted at 34 to the plates 26 and 27 is a lever 35 having a laterally extending plate 36 provided with a depression 37. When a mail bag is to be received and clamped, the plate 36 is disposed against the end of the tubular member, so that the end of the plunger rod will enter the depression. The spring 31 acting to force the plunger 29 outwardly in one direction, and owing to the arm 36 tending to move at an angle tangentially off from the line of movement of the plunger, the end of the plunger rod will frictionally bind in the depression or socket 37 of the arm 36, thereby not only holding the plunger rod back against the action of the spring 31, but also holding the arm 36 in the position shown in Fig. 1. However, as the mail bag contacts with the lever substantially at *a*, the lever will be oscillated upon its pivot, thereby withdrawing the plate 36 from the path of the plunger, which will spring outwardly and clamp the mail bag against the ring 25. The arm 24 is provided with a clip 38 to receive a loop of a mail bag, which is designed to be delivered to the receiving apparatus of the holder adjacent the track at the same time a bag is received by the mechanism on the car, and vice versa. The lever 35 of the tubular member on the car has a spring 39 connected to it and to an arm 40. The action of this spring 39 assists the lever in withdrawing the plate 36 from the path of the plunger rod. The spring 39 also throws the lever sufficiently so as to contact with the loop of the mail bag 41, in order to assist in releasing the same from the clip.

Secured in the tubular member 20 by means of the pivots or bolts or the like 42 is a handle 43. Swiveled on the handle, as at 45 is an arm 46, which, when the tubular member 20 is in position so that a mail bag will be clamped by the plunger rod, engages the floor of the car body. When the tubular member is disposed vertically this arm may be swung on its swiveled connection to a horizontal position parallel with the bar 15. The pin 30 of each plunger constitutes means to be manually gripped for setting the plunger, in engagement with its socket.

The invention having been set forth, what is claimed as new and useful is:—

1. In a mail bag exchange mechanism for mail cars, a tubular member swiveled to the car provided with a mail bag receiving arm, a spring-tensioned plunger rod in the tubular member, and a device for holding said rod against the action of the spring, said device constituting means adapted to be automatically actuated by its contact with the mail bag to release the plunger rod, said mail receiving arm having a clip adapted to

hold a bag to be delivered, said device having means for further actuating the same to assist in releasing the bag to be delivered.

2. In a mechanism for delivering and receiving mail bags to and from a moving train, a tubular member having a mail receiving arm, a spring-tensioned plunger including a plunger rod mounted in the tubular member, a lever provided with a plate including a socket to receive one end of the rod to hold the plunger back in the tubular member against the tension of the spring, said lever adapted to be automatically actuated by a mail bag to withdraw the plate from the path of the plunger rod. 75 80

3. In a mechanism for delivering and receiving mail bags to and from a moving train, a tubular member having a mail receiving arm, a spring-tensioned plunger including a plunger rod mounted in the tubular member, a lever provided with a plate including a socket to receive one end of the rod to hold the plunger back in the tubular member against the tension of the spring, 85 said lever adapted to be automatically actuated by a mail bag to withdraw the plate from the path of the plunger rod, said mail bag receiving arm having a clip to receive the loop of a mail bag to be delivered, and means to further actuate said lever to assist 90 in releasing the bag to be delivered. 95

4. In a mechanism for delivering and receiving mail bags to and from a moving train, a member provided with a plunger rod, a semi-circular mail bag receiving arm 100 connected to the member and having a ring at one end and provided with a mail bag clip, a lever pivoted adjacent the member having a plate provided with a socket to receive one end of the plunger rod, means 105 placed under tension through the medium of the rod engaging said socket to force the plunger rod outwardly to clamp a mail bag against the ring when the lever is contacted with and actuated by a mail bag. 110

5. In a mechanism for delivering and receiving mail bags to and from a moving car, a rod arranged transversely of the car door opening, a tubular member swiveled on said rod and having slots, a semi-circular mail bag receiving arm carried by one end of the tubular member and provided with a ring at one end, a clip carried by the arm substantially midway of its length to hold a mail bag to be delivered, a plunger including 115 a rod mounted in the tubular member and having a pin extending transversely thereof and through the slots, a lever pivoted adjacent the tubular member having a plate provided with a socket to receive one end of the 120 plunger rod, means placed under tension through the medium of the rod fitting the socket to throw the rod outwardly to clamp a mail bag against said ring, said lever adapted to be automatically actuated by a 125 130

mail bag contacting therewith, means for further actuating said lever to cause the same to assist in releasing the bag to be delivered, said pin of the plunger constituting means to be gripped manually for setting the plunger in engagement with the socket.

5 In testimony whereof I have signed my

name to this specification in the presence of two subscribing witnesses.
